CLOSURE CAP FOR CONTAINERS

Raymond J. Cochran, Fairfield, Conn.

Application June 15, 1956, Serial No. 41,925

Term of patent 14 years

(Cl. D58—26)

FIG. 1

Fig. 1 is a perspective view of a closure cap for containers, showing my new design; and

Fig. 2 is a cross-sectional view of the cap shown in Fig. 1.

I claim:

The ornamental design for a closure cap for containers, substantially as shown.
